UNITED STATES PATENT OFFICE

GILBERT S. VERNAM, OF RIVER EDGE, NEW JERSEY, ASSIGNOR TO INTERNATIONAL COMMUNICATIONS LABORATORIES, INC., OF NEW YORK, N. Y., A CORPORATION OF NEW YORK

PRINTING TELEGRAPH EXCHANGE SYSTEM

Application filed May 12, 1930. Serial No. 451,693.

This invention relates to printing telegraph exchange systems and more particularly applies to manually operated printing telegraph exchange systems.

- 5 The object of this invention is to supply a service whereby customers of the telegraph company, who are provided with printers connected over local lines to a so-called "concentration switch board" at a central office of 55
 10 the telegraph company, can be connected to central office printers for the purpose of receiving or sending commercial telegrams or cablegrams and whereby through the use of a "toll" switch board in the central office one 60
 15 customer's printer may be connected directly to another customer's printer in the same city or in a different city. The service provided by this toll switch board will correspond in general, to a toll telephone exchange service.
- 20 A feature of this invention is the reduction of line current to a fraction of its usual amperage when the line is idle.

A second feature of this invention is the operation of the toll line circuits "full duplex" 25 for the purpose of controlling the lamp signals so that the calling and supervisory signals may operate independently in the two directions over the line, with the automatic conversion of the circuit to "half duplex" 30 operation, when printing connections are made.

A further feature of this invention is a cord circuit for establishing "full duplex" through connections between two telegraph 35 toll lines at an intermediate switching center with provision for the connection of an operator's printer into this cord circuit so that the operator at the intermediate station can communicate with both terminal stations.

40 A further feature of this invention is the use of monitoring keys in the cord circuits whereby the toll board operator can readily cut her printer in or out of any of the cord circuits. A feature closely associated with 45 this one is the use of a splitting key in the toll board operator's printer circuit permitting the toll board operator to communicate by printer with either cord of a pair with the other cord cut off.

50 A further feature of this invention is the

arrangement whereby the customers may advise the concentration board operator by lamp signals as to the nature of the service desired.

A further feature of this invention is an 55 alternative arrangement whereby the customer may, by selective means predetermine where at the central station his call is to be answered.

A further feature of this invention is the 60 association of the signal lamps with the cord circuits rather than with the line circuits, and the arrangement whereby the lamps are lighted only when action is required on the 65 part of the operator.

An additional feature of this invention is the provision of a motor control whereby the printer motors at the customer's stations are started when the station line is connected to a printer or to a toll board cord at the central office and the provision for stopping the 70 motor from the central office or at the customer's station.

Outline of system

75

Referring to the drawings, Figure 1 shows in schematic form two groups of customers' stations, two central stations, the main apparatus at the central stations and the various methods of connecting the stations and apparatus represented.

In Fig. 1 is also shown a diagram illustrating the manner in which the several figures of the drawings are to be arranged for the purpose of obtaining a unitary disclosure 85 of the form of the invention as illustrated in Figs. 2 to 5.

Fig. 2 shows in detail the circuit of a customer's station, and the circuits of various parts of a central station viz. a concentration board, a concentration board operator's printer set, a switching trunk and a central station printer set.

Fig. 3 shows in detail the left hand portion of station to toll line cord circuit I and the circuit of station to station cord H.

Fig. 4 shows in detail the right hand portion of the station to toll line cord circuit I, the toll line to toll line cord circuit K and 100

the left hand portion of the toll board operator's printer set circuit L.

Fig. 5 shows in detail in circuit J the apparatus at one end of a toll line, similar apparatus being located at the distant end of the line at station M the direction of which is indicated but which is not shown; this figure also shows the right hand portion of toll board operator's printer set circuit L.

Fig. 6 shows in detail the circuit of customer's station O similar to circuit C of Fig. 2, and in circuit P a portion of a toll board and two concentration board signal panels at a central station showing their use with a selective call system.

Fig. 1 illustrates in outline, the proposed manual printer exchange system. While for purposes of illustration only five customers' stations are here shown as associated with central station A there may be a large number of such stations and all the circuits have been so arranged that the whole system can be expanded with facility to handle an indefinite number of new customers' stations as well as new central stations. Thus the concentration board station connections may be readily increased and the number of concentration board and central stations operators' printers can be increased to serve the additional local stations. Also the number of station to station, station to toll line and toll line to toll line cords, may vary in number according to the requirements of the traffic, only one of each type being shown, however, in this figure. Obviously there may also be any number of station to station toll lines coming into each toll board. It will therefore be understood that in the description of the system in the ensuing pages typical hook-ups will be presented and no attempt will be made to point out all the connections that might possibly be made.

In regard to the expansion of the system illustrated attention is particularly called to certain specific points in the circuits where expansion may take place. At the following points the ground connections may be made through auxiliary signal circuits; Fig. 2, circuit D, at 724; circuit F, at 710, 711 and 712; Fig. 3, circuit I, at 713; circuit H, at 714; Fig. 4, circuit I, at 715; circuit K, at 716 and 717; Fig. 5, circuit J at 718; circuit L at 719; Fig. 6, circuit P at 720, 721, 722 and 723. At point 204 in circuit F, Fig. 2, point 708, in circuit J, Fig. 5 and point 709 in circuit P, Fig. 6, additional lamps and jacks may be inserted. In Fig. 3, circuit H, at points 703 and 704 additional monitoring keys might be inserted for use with additional cord circuits, likewise in Fig. 4, at points 705, 706 and 707. No attempt has been made, however, to point out all the specific points at which expansion of the system might take place.

Likewise it will be understood that there

may be any number of additional central stations with associated local lines, and that these various central stations may be connected one to another over the various toll lines in some cases directly and in other cases through an intermediary central station or several intermediary central stations, and any one customer's station associated with one of the central stations may thereby be connected with any other customer station associated with that particular central station or with any other central station.

In Fig. 1 customers' stations 1 to 5, are shown connected by telegraph lines 6 to 10 to the concentration board jacks 11 to 15.

Connected to an additional jack 16 on the concentration board is a concentration board operator's printer 17 by means of which the concentration board operator may communicate with the toll board operator. Cords 18, 19 and 20 at the concentration board lead to central station operators' printers 21, 22 and 23. These printers are used for receiving telegrams and cablegrams from the customers' stations. Cords 24, 25 and 26 are respectively connected to switching trunks 27, 28 and 29 leading to the toll board of central station A, at which point they are connected to jacks 30, 31 and 32. The switching trunks 27, 28 and 29 are used to connect the concentration board with the toll board for various types of service. They may connect any two of customers' stations, 1 to 5 through the toll board by means of station to station cord 35. They may also be used for connecting one of the customers' stations 1 to 5, to a central station other than central station A through station to toll line cord 38, connection with the distant central station being made through one of the telegraph toll lines 39, 40 or 41 associated with the toll board jacks 42, 43 and 44, respectively, each of which lines may be connected to a different central station.

The third cord 45 at the toll board is known as the toll line to toll line cord and may be connected to any two of the toll lines 39 to 41 through plugs 46 and 47. In the toll board cord circuits 35, 38 and 45, monitoring keys 48, 49 and 50 are respectively inserted. By means of these monitoring keys the toll board operator's printer 51 may be connected to any one of the three cord circuits. Central station B together with its customers' stations and lines and toll lines, is a duplicate of central station A and its auxiliary lines and has therefore not been specifically described.

The operation of the system for the purpose of sending telegrams or cablegrams through central station A will be clear if it is stated that any one of the customers' stations, 1 to 5, desiring to send a telegram or cablegram is connected by the concentration board operator with one of the central sta-

tions operators' printers 21, 22 or 23 where the message is received.

If one of the customers' stations associated with central station A desires to communicate

- 5 with a second customer's station associated with station A, the local stations are connected through two concentration board switching trunks such as 28 and 29 and a station to station cord 35 at the toll board.
- 10 Connections may be made between a customer's station associated with central station A and a customer's station associated with central station B through the concentration board of central station A, a switch-
- 15 ing trunk such as 27, a station to toll line cord 38 and toll line 39, 40 or 41 to the toll board of central station B and thus in reverse order from the toll board at central station B, over a switching trunk to the concentration board of central station B and so to the customer's station associated with central station B with which communication is desired.

Where central station A is used as an intermediate station for connecting two other central stations, connections will be made over two of the toll lines 39, 40 and 41 by means of a toll station to toll station cord 45 the circuit thus passing through only the toll board of the intermediate station.

Customer's station circuit

In Fig. 2, customer's station C is shown connected to a concentration board D and associated therewith is shown concentration board printer set E, switching trunk F and central station printer set G.

At the customer's station C, polar relay 101 is connected in series with customer's 40 telegraph line 102 joining the customer's station C with concentration board D at the central station. This relay 101 has two windings, connected in series, one of low resistance 103 and one of high resistance 104, 45 and is equipped with a biasing spring 105 which tends to move the relay armature 106 against contact 107. Relay 101 will be released and will close contact 107 on the application of a positive potential to line 102 at 50 the central station. In the normal or idle condition of the customer's station circuit, this relay is held energized by a negative current of about 6 milliamperes passing through both windings 103 and 104 in series. This 55 current may be traced from ground 108, through negative current source 109, at concentration board D, through conductor 110, protective resistance 111, conductor 112, through the winding of marginal relay 113, 60 and conductor 114 to normally closed jack contact 115 and thence through resistance 116 and over customer's line 102 through windings 103 and 104 of relay 101 in series, over conductor 117 through printer line mag- 65 net 118, transmitter 119 and "recall" or

"break" key 120 to ground 121. Under these conditions, relay 101 will be operated but marginal relay 113 will not be affected by this strength of current.

In the case of a call, either from a central 70 station printer 122 in central station printer circuit G of this figure (21, 22 or 23 of Fig. 1) or from the toll board (see Fig. 1), a cord plug will be inserted in one of the line jacks 123 of the concentration board with the result that a positive potential will be applied to customer's station line 102. The method of applying this positive potential to the cord circuits will be described later.

The application of the positive potential 80 reverses the direction of the current in relay 101, which was previously held operated by a negative potential, and it thereupon releases armature 106 which closes contact 107. A current is thereby passed from terminal 124, 85 of a local A. C. or D. C. source over conductor 125 through resistance 126, conductor 127, through winding of control relay 128, conductor 129, to back contact 130 of relay 131, across armature 132, conductor 133 to contact 107 and thus through conductor 134, resistance 135 and conductor 136 to the opposite terminal 137 of the current supply. The closing of this circuit operates control relay 128 which closes its contacts 139 and 138 there- 95

by respectively, putting into operation printer motor 140, and short-circuiting high resistance winding 104 of relay 101. The line current now increases to its usual working value of about 60 milliamperes. Resistance 100 116 in customer's line 102 is included in the circuit to regulate the current to this value and to compensate for variations in the resistances of the line wires to different stations. Under these conditions, printer signals may 105 be sent from the sending contacts of customer's station transmitter 119 or from those of a central office or distant printer, and these signals will operate the respective printers without operating relay 101 since spring 110 105 gives the relay a positive bias. If a negative potential is again applied to the line, however, the reversal of current will operate relay 101 to pull up armature 106 and break the circuit through the control relay 128 at contact 107, causing the control relay 128, to release, thus stopping printer motor 140 and re-inserting the high resistance winding 104 of relay 101 into the line circuit. The circuit is 115 now restored to its original or idle condition 120 and a negative current of approximately 6 milliamperes is passing through the circuit.

In the case of a call originating at customer's station C, the customer's operator operates calling key 141 in a direction to close 125 contacts 142, which short-circuits the high resistance winding 104, of relay 101, thus increasing the line current from approximately 6 to 60 milliamperes. The calling key 141 is a three position lever type key arranged so 130

that the lever will lock in the calling position or in the normal position but when operated to the releasing side (for purposes to be described later) the key is non-locking and will 5 restore itself to the normal position when released by the operator.

If the key is left in the calling position, the increased line current will operate marginal relay 113 at concentration board D, 10 which relay, will in turn operate relay 143 of the concentration board circuit which locks itself through a circuit traced from ground 144 through contact 145, jack contact 146, conductor 147, current source 109 15 and ground 108. Under these conditions current will be applied to "toll" lamp 148 at concentration board D over a circuit which may be traced from ground 149, contact 150 of relay 143, conductor 151, front contact 20 152 of relay 113, conductor 153, conductor 154, current supply 109 and ground 108, lighting the lamp and indicating that a connection with the toll board is desired.

If, on the other hand, calling key 141 at 25 customer's station C is operated to the calling position and then restored to normal, the relays 113 and 143 will operate as described and then relay 113 will release, with the result that the "message" lamp 155 will 30 be lighted, indicating that the customer wishes a connection with a central station printer to record an outgoing telegram or cablegram. In either case, relay 101 of customer's station C will not be released until 35 a positive current is connected through the concentration board to customer's line 102, as previously described. The insertion of a cord plug into the jack 123 at concentration board D will obviously release relays 113 and 40 143 by breaking the operating circuits of these relays at contacts 115 and 146 respectively extinguishing whichever lamp is lighted.

After a connection has been established 45 and relay 101 has been released and control relay 128 operated at the customer's station, the customer may send a disconnect signal to the central station by operating key 141 momentarily to the release position thus 50 closing contact 156 which closes a circuit commencing at terminal 137 of the local current source and consisting of conductor 136, resistance 135, conductor 134, contact 107, conductor 133, conductor 157, contact 156, 55 conductor 158, winding of relay 131, resistance 126, and conductor 125 to the opposite pole 124 of the current source. Relay 131 is thus operated and locks itself through its front contact 159 thus breaking the operating circuit of control relay 128 at contact 130 and releasing said control relay which in turn stops printer motor 140 by breaking contact 139 and connects the high resistance winding 104 of relay 101 into the line circuit by breaking contact 138. The resultant

reduction in the current in customer's line 102 acts to light supervisory signals in the various cord circuits at the toll board as will be described later. When the circuit is disconnected at the central office, a negative current from source 109 is again applied to customer's line 102, relay 101 will be operated and the locking circuit of relay 131 broken at contact 107 of relay 101, thus releasing relay 131 and restoring the circuit to normal. 75

Central station printer set circuit

As was indicated in Fig. 1 the central station apparatus and circuits consist generally of concentration board D, concentration board operator's printer set E, switching trunk F, central station printer circuits G, station to station cord circuits H, station to toll line circuits I, toll line circuit J, toll line to toll line cord circuit K and toll board operator's printer set circuit L. Circuit G of Fig. 2 illustrates the circuit of the printer set at the central telegraph office used for sending and receiving telegrams and cablegrams. In the idle condition, all of the relays in this circuit are released as illustrated and the printer motor 160 is stopped. To prepare this circuit for the transmission of messages the plug 161 which is located at the central station concentration board, is inserted into jack 123, by the concentration board operator thus connecting the central station printer set circuit G with customer's station C through line 102, the control relay 162 will be operated to start motor 160, 90

light the guard lamp 163, and to supply current for the local circuits of the printer as well as to connect a positive current from current source 164 to the customer's station line 102. The circuit for operating the control relay may be traced from ground 108 at concentration board D through current source 109, protective resistance 165, conductor 147, jack contact 166, sleeve of jack 123, sleeve contact of plug 161, conductor 169, junction point 199, conductor 170, key 171, conductor 172, back contact 173 of sleeve relay 174, conductor 175, conductor 176, and so through winding of relay 162 to ground 177. 105

It will be seen that the operation of relay 162 closes contact 168 which connects current source 164 through contact 168 to junction 178 from which current flows through resistance 179 to guard lamp 163 and thus to ground 180 and also from junction 178 over conductor 181 to printer motor 160, transmitter 122, line relay 182 and so through conductor 183 to back contact 184 of sleeve relay 174, from which the current is passed through conductor 185, tip of plug 161, to jack 123 and so through customer's line 102 to customer's station C as above indicated where motor 140 is started. The sta- 110

115

120

125

130

tions now are ready for the transmission of messages.

It should be noted, that no battery is supplied to the sleeve of jack 123 until after cord plug 161 has been inserted, and as the resistance of control relay 162 is comparatively low, the voltage on the sleeve of plug 161, when it is inserted in the jack is so low that it is impossible for the operator to receive a shock from the circuit, except possibly from an inductive discharge from the winding of control relay 162 or the winding of sleeve relay 174 when the cord plug 161 is pulled down. This could be avoided, if necessary, by connecting a resistance from the sleeve of plug 161 to the ground. The same general method of preventing shocks is used for all the jacks and plugs on the toll board.

When communication between the stations has been completed, the central station printer operator momentarily operates release key 171. This breaks a connection through conductor 172, contact 173, and armature 175, which short-circuits the winding of sleeve relay 174, thus permitting relay 174 to operate in series with the control relay 162 and on being energized, sleeve relay 174 itself opens the short-circuit at back contact 173, so that it will not release when the contacts of release key 171 are again closed. It also short-circuits the winding of control relay 162 by grounding itself through its front contact 187 and ground 188, thus releasing control relay 162, which opens contact 168 thus cutting off the current from guard lamp 163 and conductor 181 and stopping the printer motor 160. Sleeve relay 174 also applies a negative current from source 189 through the winding of the marginal recall relay 190 to the station line circuit by means of conductors 191, front contact 192 of sleeve relay 174 and conductor 185, and tip of plug 161. This current operates relay 101 at the customer's station C to pull up armature 106 which opens a circuit to stop printer motor 140 as previously described. Sleeve relay 174 also passes a negative current from current source 189 through resistance 193, conductor 194, contact 195, conductor 196, and disconnect lamp 197 to ground 198, which circuit lights disconnect lamp 197 located at the concentration board as a signal to the concentration board operator to pull down cord plug 161. As a negative potential has already been applied to customer's line 102 from source 189 with the result that the line current has been reduced to approximately 6 milliamperes by the release of the control relay 128 at customer's station C, the marginal relay 113 at concentration board D will not operate when plug 161 is withdrawn at the concentration board. When this plug is withdrawn, however, negative current from source 109 is cut off from the sleeve of plug 161, sleeve relay 174 is released and by reason of the breaking of the

circuit at its contacts 195 and 192, respectively, negative current from current source 189, is removed from disconnect lamp 197 and from tip of plug 161, and the circuit is restored to its normal or idle condition.

If the concentration board operator should be slow to disconnect and the customer's operator should wish to place another call, call key 141 at customer's station C may be operated to close contacts 142 to increase the negative 6 milliamperes current to a negative current of approximately 60 milliamperes as previously described. Under these conditions, the recall relay 190 of printer set G, which is a marginal relay operable on a current of 60 milliamperes but not on a current of 6 milliamperes, and which is connected through front contact 192 of sleeve relay 174 to the customer's line, will operate and short-circuit sleeve relay 174 through a circuit traced from junction 199, through conductor 170, release key 171, conductor 172, contact 200, armature 201, conductor 202, winding of control relay 162 and ground 177. Sleeve relay 174 having been released will disconnect the circuit operating recall relay 190 through contact 192. Recall relay 190 is shunted by resistance 203 to make it slightly slow to release thereby preventing it from releasing until sleeve relay 174 has been completely released. The release of sleeve relay 174 also removes the short-circuit from control relay 162 which thereupon operates, closes contact 168 which passes a current from current source 164 to junction 178 thus lighting the guard lamp 163 and passing a current through conductor 181, to start printer motor 160 and also passing a positive current through transmitter 122, conductor 183, contact 184, conductor 185 to the tip of plug 161 and so through customer's line 102 to customer's station C where, by previously described operations, motor 140 is started, thus restoring the circuit to its working condition. The customer's operator may now communicate by printer with the main station operator.

Switching trunks

The switching trunk circuit is shown at F 115 of Fig. 2, (see also switching trunks 27, 28 and 29 in Fig. 1). This circuit serves to extend the connections in either direction between the concentration board and the toll board. If the toll board has more than one 120 position, the circuits can be multiplied at the toll board as indicated in the drawings, (204 of circuit F, Fig. 2). If there are several concentration boards, each board will have its own group of trunk lines to the toll board, 125 sufficient trunk lines being provided to handle the peak load.

If the "toll" lamp 148 at concentration board D, which is associated with customer's station line 102 lights indicating that cus- 130

- 5 tomer's station C wishes to place a toll call, the concentration board operator will insert plug 205 of an idle switching trunk into the station line jack 123. This will extinguish 70 toll lamp 148, by separating contacts 115 and thus releasing relay 113, as previously described. It will also operate sleeve relay 206 at the switching trunk F, which by closing contact 207 will extend the line circuit 10 from customer's line 102 through jack 123, tip of plug 205, conductor 208, contact 209 of jack 210 through conductor 211, similarly through contacts of jacks at any other toll board positions as indicated by dotted lines 15 at 204 and finally through contact 213 of jack 212, conductor 214 and winding of marginal relay 215, resistance 216, negative current source 217 to ground 218. Marginal relay 215 is thereby operated, closing contact 219 20 and thus closing circuit from ground 220, through positive current source 221, resistance 222, contact 223, conductor 224, contact 219, conductor 225, call lamps 167 and 226 to grounds 186 and 227 respectively, thereby 25 lighting the call lamps 167 and 226 which are located at the toll board. Relay 206 in operating also short-circuits resistance 228, thus preparing a circuit for later operating the guard lamp 229 located at the concentration 30 board.

This call may be answered by inserting plug 230 (Fig. 3) of station to station cord H or plug 231 (Fig. 3) of station to toll line cord I into the switching trunk jack 210 at 35 the toll board or into the corresponding jack for this trunk at any other toll board position such as jack 212. The details of these cord circuits will be explained later. The insertion of one of these plugs places ground 40 on the sleeve of jack 210 through sleeve of plug 231, conductor 233, winding of relay 451, conductor 452, winding of relay 234 and ground 235. From the sleeve of jack 210 the ground is connected through contact 45 236, conductor 237, contact 238, conductor 239, winding of relay 240, resistance 241, to positive current source 221 and so to ground 220, thus operating busy relay 240 of switching trunk F, which, by opening contact 223, 50 extinguishes call lamps 167 and 226 and also closes a circuit through busy lamps 242 and 243, traced from ground 220, through positive current source 221, resistance 244, contact 245 of relay 240, conductor 246, to junction point 55 247 and thus over conductor 249 and through busy lamp 242 to ground 248 and from junction point 247 again over conductor 249 through busy lamp 243 to ground 250 and similarly through busy lamps at other positions 60 as indicated by the multiple connections at 204. The insertion of a cord plug into jack 210 or the corresponding jack such as 212 at another position also opens contacts 209 thus removing ground from marginal relay 215 65 which consequently releases. The tips of

cord plugs 230 and 231 (Fig. 3) are both connected to positive current sources as will be later detailed. On the insertion of one of these plugs in jack 210, the source of positive potential is applied to the customer's 70 line 102 through conductor 208, contact 207, tip of plug 205 and jack 123. As previously explained, this positive current will start printer motor 140 at customer's station C. 75

In the case of a call from the toll board 80 for a station line, the toll board operator inserts a cord plug 230 or 231 (Fig. 3) into an idle switching trunk jack such as 210. This closes contact 236 and thus places the ground associated with the sleeve of plugs 85 230 or 231 on conductor 237 and passes it through resistance 228 (relay 206 being unoperated) over conductor 239 and through the windings of busy relay 240, through resistance 241, source of potential 221 to ground 220. Resistance 228 in this case, so limits the current from source 221 that marginal sleeve relay 234 (Fig. 3) of cord I or marginal relay 251 (Fig. 3) of cord H, 90 cannot operate. Busy relay 240 on being 95 operated, closes its contact 245 and, as previously explained, lights the busy lamps 242 and 243 and also closes a circuit through ground 220, source of positive potential 221, resistance 222, contact 252, conductor 253, contact 254, through guard lamp 229 and similarly through guard lamps at other positions as indicated by the dotted line at 710 to ground 255, thus lighting the guard lamp 100 at the concentration board advising the concentration board operator of the outgoing call. The toll board operator then informs the concentration board operator of the number of the called station. This may be done by using a separate order wire operating by 105 telephone, by printing telegraph, by manual telegraph means or the switching trunk cord plug 205 may be inserted into jack 256 of the concentration board printer set E (see also 117 of Fig. 1), the operation of which will be 110 obvious to those skilled in the art, and the necessary information sent directly over the trunk circuit.

The concentration board operator will then 115 insert the switching trunk plug 205 into jack 123 of the called customer's station line, this will apply a negative current from current source 109 at concentration board D to the sleeve of jack 123 which in turn will pass the current through the sleeve of plug 120 205 to the winding of sleeve relay 206 of switching trunk F, thus operating relay 206 which opens contact 254 and thus extinguishes guard lamp 229. Relay 206 by closing contact 238 shunts resistance 228, placing sufficient additional current from source 221, on the coils of marginal relay 234 (Fig. 3) of cord I or 251 (Fig. 3) of cord H, to operate it, thus applying a positive current from source 437 (Fig. 4) or source 130

291 (Fig. 3) to the tips of cord plugs 231 or 230 respectively, from which point it is passed through jack 210 and through switching trunk F to jack 123 of concentration board D and so through line 102 to customer's station C where it will start the motor 140 as previously described.

When the call is completed, the toll board operator pulls down the cord plug from switching trunk jack 210 which breaks contact 236, releasing busy relay 240 and closing contact 209 of jack 210 thus re-establishing the circuit through the winding of marginal relay 215 to the negative current source 217. This operates relay 101 and releases relay 128 at the customer's station, and as the call key 141 is in its normal position, the current will be reduced to about 6 milliamperes. Relay 215 may operate momentarily immediately after the removal of the plug, but it will release when the line current is reduced. As relay 240 is released, and sleeve relay 206 remains operated, the circuit from current source to guard lamp 229 is closed and the lamp will light. Contact 245 being opened on the release of relay 240 the busy lamps 242 and 243 will be extinguished. Under these conditions, the concentration board operator should pull down the switching trunk cord plug 205, restoring the circuit to normal. However, if the operator at the customer's station should operate the call key 141 (closing contact 142) to place a new call, before the switching trunk cord plug 205 has been pulled down, high resistance winding 104 of relay 101 will be removed from the customer's line circuit and the current increased from approximately 6 milliamperes to 60 milliamperes and marginal signal relay 215 of switching trunk F will then operate to light call lamps 167 and 226 at the toll board and by opening contact 807 will also extinguish the guard lamp 229, whereupon the toll board operator will plug into the line again at jack 210.

Station to station cord circuit

The cord circuit for connecting a customer's station to another similar station in the same city is shown in Fig. 3 as circuit H. Referring to this circuit the action of the repeating relays 257 and 258 will be described first and it will be assumed for the purpose of explanation that connection has already been established between the two customers' stations and that, further, the front and back plugs 268 and 230 respectively, have been inserted into the jacks 210 of two separate switching trunks, which are extended through the concentration board D to station C of the called and calling customers, respectively. Relays 206 and 240 of switching trunk F (Fig. 2) will, therefore, be energized as well as the control relays 128 at the customer's station C (Fig. 2) and the sleeve relays

251 and 259 of the station to station cord circuit H will also be operated. The polar repeating relays 257 and 258 will be energized in a direction to hold their respective armatures 259 and 260 against marking contacts 261 and 262 respectively.

The two left hand windings 263 and 264 of relay 257 and windings 265 and 266 of relay 258 are differentially connected, windings 263 and 265 being connected to ground through the concentration board and the station line, which circuit may be traced, for winding 263, through conductor 808 through front contact 267 to the tip of plug 268 and so through a switching trunk F (Fig. 2), and concentration board D to customer's line 102; for winding 265 through conductor 269, contact 270 of monitoring key 306, conductor 271, front contact 272 of relay 251, to tip of plug 230, and so through a second switching trunk F (Fig. 2) and concentration board D to a second customer's line 102. Windings 264 and 266 are carried to ground through artificial lines 273 and 274 consisting respectively of resistance 275 and inductance 276 and resistance 277 and inductance 278. From junction point 279 where the artificial lines unite a circuit may be traced over conductor 280 to junction point 282 and through conductor 283 and contact 284 of sleeve relay 259 to ground 285. The circuit through the windings 263, 264, 265 and 266 are not exactly balanced, the current through 263 and 265 being nearly twice that of windings 264 and 266. As long as both circuits on each relay remain closed, the relay armatures will remain against their marking contacts 261 and 262 respectively, but if the circuits of line winding 263 or 265 is opened by an open signal impulse sent from its respective customer's station C, the relay armature 259 or 260 respectively, will be moved to its spacing contacts 286 or 287 respectively under the influence of the current in the artificial line winding.

It is evident, therefore, that each of these relays will respond to signals sent from the station to which its line winding is connected. When so operated, each relay will repeat these signals through the windings of the other relay into the other station line, thus, if the line to which winding 263 of relay 257 is connected is closed at the called customer's station C, (Fig. 2) a current will be sent through a circuit as follows: from ground 290, of station to station cord H through source of positive potential 291, conductor 292, junction point 293, resistance 294, armature 260, marking contact 262, conductor 296, back contact 297 of "cut" relay 298, conductor 299 to junction point 288 and thus through winding 263 of relay 257 and through conductor 808, contact 267 of relay 259 to the tip of plug 268 and thus through a switching trunk F (Fig. 2), through the concentration board D to cus-

- 5 tomer's line 102 and so to ground 121 at customer's station C. Relay 257 (Fig. 3) will then close its marking contact 261 and cause a current to pass from source of positive potential 291, associated with ground 290, through conductor 292, junction point 300, resistance 301, conductor 302, armature 259, marking contact 261 of relay 257, back contact 303 of cut relay 298, conductor 304 to junction point 289 and thus through winding 265 of relay 258, conductor 269, contact 270 of monitoring key 306, conductor 271, contact 272 of relay 251, to the tip of plug 230 and thus over a second switching trunk F (Fig. 15 2), through concentration board D to a second customer's line 102 to the calling customer's station C where the printer magnet 118 will be operated and finally to ground 121.
- 20 Winding 305 of relay 257 and winding 295 of relay 258 have less turns than the other two windings of these relays and the currents through them have comparatively small magnetic effects in a direction tending to aid the line windings 263 and 265, respectively, in holding the respective armatures against the marking contacts. This does not interfere with the repeating action described above, but serves to hold the armatures against the 25 marking contacts when no current is flowing through either of the other windings. Therefore, when the relay 257, for instance, repeats signals through relay 258, the latter relay will not respond to these signals as its armature 260 is held against its marking contact 262 by winding 295 when windings 265 and 266 are open at relay 257, that is to say, when spacing contact 286 of relay 257 is closed, armature 260 is held against marking contact 40 262 by winding 295 and when armature 259 reverses and contact 261 is closed armature 260 is still held against contact 262, but this time by winding 265. The inductances 276 and 278 associated with relays 257 and 258, 45 which are in series with artificial line windings 264 and 266 respectively, prevent the current in these windings from rising more rapidly than in the line windings 263 and 265 when the line circuits are closed, thus balancing the inductance of the printer line magnets 118 at the customer's stations C (Fig. 2).
- 50 It should be noted that the line circuit from the tip of cord plug 230 to the line winding 265 of relay 258 extends through normally closed contact 270 of the monitoring key 306. When this key 306 is operated, the sending contacts 307 and line relay 318 of the operator's printer in operator's set circuit L (Fig. 4) are connected in series with the line at this point. This circuit can be traced as follows: from junction point 308 (Fig. 3) of monitoring key 306 through contact 309, conductor 310, contact 311 of monitoring key 312, (also through contacts sim-

ilar to 311 of monitoring keys for other cord circuits indicated by dotted lines 704 and 705) conductor 313, contact 314 of split key 315 (Fig. 4), conductor 316, winding 317 of polar relay 318, conductor 319, contact 320 of monitoring key 321, (also through contacts similar to 320 of monitoring keys for other cord circuits as indicated by dotted line 706) conductor 322, contact 323 of monitoring key 321, conductor 324, key 325, toll board operator's transmitter 307, conductor 326, contact 327, conductor 328, contact 329 of monitoring key 312, conductor 330, contact 331, to conductor 271 in station to station cord circuit H. The contact springs of the monitoring key 306 are so arranged and adjusted that the key can be operated or restored to cut the toll board operator's printer unit (key 325, transmitting contacts 307, line relay 318 and printing magnet 578) in or out of the circuit without momentarily interrupting the station line circuit. Also if two or more monitoring keys are operated together in error, this will not interfere with the communication between the customers, but the operator's printer will be connected to the cord circuit whose monitoring key is nearest to the operator's set in the circuit, viz., if the monitoring keys 306 and 312 are both operated at the same time, the operator's printer will be connected to the station to toll line cord I, (Figs. 3 and 4) rather than to station to station cord H whose monitoring key 306 is further from the operator's printer and whose circuit is closed at contact 800 on the opening of monitoring key 312. It is to be noted that a monitoring key associated with a toll line to toll line cord K (Fig. 4) should not be operated at the same time as that of one of the other types of cords as this would permit signals to be repeated from one cord circuit to another.

55 The split key 315 of the toll board operator's printer set circuit L (Fig. 4) may be used if the operator wishes to communicate with one customer's station C and at the same time cut off the other customer's station C. For example, if this key is operated in a direction to open the contact 314 and close contacts 332, 333 and 334, the operator's printer will be connected through cord plug 230 of station to station cord H, since the opening of contact 314 and the closing of contact 332 cuts off the return circuit to relay 258 (Fig. 3) and instead closes the circuit through contact 332, over conductor 335 (Fig. 5), junction 336, resistance 337 to source of positive potential 338, and ground 339. The line winding 265 of relay 258 (Fig. 3) will, therefore, be connected through to contact 333 of split key 315 (Fig. 4) through conductor 340, winding 341 (Fig. 5) of supervisory relay 342, conductor 343, to contact point 344 and through resistance 345, which resistance 60 120 125 130

is equivalent to that of a station line and then to ground 346.

The circuit just traced energizes relay 342 which opens contact 347 thus preventing relay 348 from operating. The operator may now communicate directly with the station connected through cord plug 230 (Fig. 3) and these signals will not be repeated through the station connected through cord plug 268 (Fig. 3). The station connected through the latter plug may, however, recall the operator by holding recall key 120 at customer's station C (Fig. 2) operated for a few seconds. This will open the line and release supervisory relay 342 (Fig. 5) closing contact 347. After a short interval, relay 348 which is a slow to operate relay will operate over a circuit traced from ground 349 (Fig. 4) of the split key circuit, contact 334, conductor 350, contact 347 (Fig. 5) through winding 351 of relay 348 through resistance 352 and through source of positive potential 353 to ground 354. The operation of relay 348 closes the operating circuit of guard lamp 355 at contact 356 thereby lighting the lamp and relay 348 locks itself at contact 357 to hold the guard lamp lighted until split key 315 is restored to normal.

If the split key (Fig. 4) is operated in the opposite direction to close contacts 358, 359, 360, and open contact 327, the line winding 235 of relay 258 (Fig. 3) will be connected through the operator's printer and through resistance 345 to ground 346 while the line circuit operating through cord plug 230 (Fig. 3) will be connected to positive current source 338 (Fig. 5) through contact 359 (Fig. 4) conductor 701 and winding 361 of relay 342 (Fig. 5). Under these conditions, the operator may communicate through relays 257 and 258 (Fig. 3) with the station connected through cord plug 268, while the station connected through cord plug 230 will be in position to operate guard lamp 355 (Fig. 5) as previously described for the reverse situation.

Referring again to station to station cord H, (Fig. 3) the action of sleeve relays 251 and 259 will be described. Assuming that a call from a customer's station has been extended through the concentration board D (Fig. 2) and over a switching trunk F to the toll board, the toll board operator will then insert cord plug 230 (Fig. 3) in jack 210 of the switching trunk F. This will close the circuit from ground 281 (Fig. 3) through the winding of sleeve relay 251, sleeve of plug 230 and contact 236 (Fig. 2) of jack 210, through winding of relay 240 to current source 221 and ground 220 at the switching trunk F. This will operate relay 240 of the switching trunk which will extinguish call lamps 167 and 226 and light the busy lamps 242 and 243 as previously described. It will also operate sleeve relay 251 (Fig. 3) of sta-

tion to station cord circuit H. This relay connects ground to the various windings of the repeating relays 257 and 258 as will be clear from the illustration of circuit H. It also extends the station line circuit from the tip of cord plug 230 through relay 258 by closing front contact 272 of relay 251. The operation of relay 251 as previously stated, places a ground on winding 305 of relay 257 and winding 295 of relay 258. These windings thereupon cause their respective relays to operate and each relay connects a positive current to the line and artificial line windings of the other relay.

The circuit of the line winding of relay 258 extends to calling customer's station C (Fig. 2) as previously traced where by reason of the positive current carried over said line from current source 291 (Fig. 3) of station to station cord circuit H, relay 101 (Fig. 2) is released and printer motor 140 started as previously described. The circuit of the line winding of relay 257 (Fig. 3) extends through back contact 365 of sleeve relay 259 and through resistance 366 which is equivalent to a station line.

The operator may now operate the monitoring key 306 and communicate with the calling customer's station C as previously described. After ascertaining the number of the called line, cord plug 268 will be inserted into jack 210 (Fig. 2) of an idle switching trunk F. As previously explained in connection with the operation of sleeve relay 251, this will extend a ground connection to the relay 240 of switching trunk F through the sleeve of cord plug 268 and contact 236 of jack 210 but as the circuit has not yet been extended to a called customer's station C, relay 206 of the switching trunk circuit

F has not been operated and consequently resistance 228 is still in the circuit and sleeve relay 259 (Fig. 3) will not be operated since insufficient current passes through resistance 228 to operate it. Guard lamp 229 (Fig. 2) will be lighted by the operation of relay 240 and consequent closing of contact 252.

When the concentration board operator replies, the toll board operator gives her the number of the called station. Whereupon the concentration board operator inserts switching trunk plug 205 into jack 123 associated with the called station line 102, which connection extends negative current from current source 109 at concentration board D through jack 123 and sleeve of plug 205 to relay 206 of switching trunk F which operates to short-circuit resistance 228 enabling sufficient current to be passed from current source 221 of the switching trunk through contact 236 and jack 210 of switching trunk F and sleeve of cord plug 268 (Fig. 3) to operate sleeve relay 259 of station to station cord circuit H thereby closing contact 267 and connecting winding 263 of relay 257 with

110

115

120

125

130

- the called customer's station. On completion of line connections with the called customer's station C, positive current is passed from source of positive current 291 through 5 conductor 292 to junction point 293, resistance 294, armature 260, marking contact 262, conductor 296, contact point 297, conductor 299, winding 263 of relay 257, conductor 808, contact 267 through the tip of cord plug 10 268, through switching trunk F (Fig. 2) and so through the concentration board and customer's line 102 to the called station C where the motor 140 is started as was previously described whereupon the calling and 15 called customer's stations C may now communicate with each other. The toll board operator should restore monitoring key 306 to normal as soon as communication is satisfactorily established.
- 20 When the call is completed, the operator at each customer's station momentarily operates relay key 141 closing contact 156 which operates to lock relay 131 and release control relay 128 as previously described. This 25 stops station motor 140 and reduces the line current to approximately 6 milliamperes. Assuming that the calling customer's station C connected through cord plug 230 (Fig. 3) of station to station cord circuit H, operates 30 release key 141 first, relay 258 (Fig. 3) of station to station cord circuit H, will release but as this opens a circuit at contact 262, to both windings 263 and 264 of relay 257, relay 257 cannot release at this time by reason 35 of the effect of winding 305 even though the called station, connected through cord plug 268, also operates its release key 141.
- Relay 258 thereupon closes a circuit from its spacing contact 287 as follows: from current source 291 associated with ground 290 40 through conductor 292, junction point 293, resistance 294, armature 260, contact 287, conductor 367, resistance 368, winding of relay 363, junction point 370, conductor 371, contact 372 of monitoring key 306, conductor 373, conductor 374 through contact 375 of relay 251 to ground 281. Relay 363 is a slow acting relay which will not operate on short impulses due to printer signals but 45 will operate when armature 260 of relay 258 remains against its spacing contact 287 for a longer interval. Relay 363 being operated, closes its contact 376 and thereby places ground 377 in the circuit of supervisory lamp 378 associated with cord plug 230 thus applying current from source 291 to the lamp and lighting it. Relay 363 also closes contact 379, which places ground 380 on the "cut" relay 298. The cut relay operates, and 50 by closing contacts 381 and 382, applies positive current directly to windings 263, 264 and 265, 266 of relays 257 and 258 respectively over circuits traced as follows: for relay 257 from ground 290 through current source 291, conductor 292, junction point 293, resistance 60 65

294, conductor 383, contact point 382, conductor 299 to junction point 288 and so through windings 263 and 264; for relay 258 from ground 290 through current source 291, conductor 292, junction point 300, resistance 301, conductor 302, to contact point 381, conductor 304 to contact point 289 and so through windings 265 and 266 of relay 258. Relay 363 in effect, therefore, cuts the repeater so that a signal sent into one side of the repeater will now have no effect on the line circuit of the other side of the repeater. If the release key 141 (Fig. 2) at the called customer's station C, connected to cord plug 268 (Fig. 3) of station to station cord H, has been operated by this time, relay 257 will now release by reason of the insertion of high resistance winding 104 (Fig. 2) into the circuit at the called customer's station C and after an interval relay 362 (Fig. 3) 70 75 80 85 90 95 100 105 110 115 120 125 130 will operate and light supervisory lamp 384 associated with cord plug 268, in the same manner as described for the lighting of supervisory lamp 378. When both supervisory lamps 378 and 384 are lighted, the toll board operator will pull down both cord plugs 230 and 268. This will operate relay 101 (Fig. 2) at both customer's stations C which action will release relay 131 at both customer's stations and will light guard lamps 229 associated with customer's stations lines at the switching trunk circuit F, to signal the concentration board operator to disconnect, as previously described. The cord circuit relays 251 and 259 (Fig. 3) will also be restored to normal which will remove the ground from the relays 362 and 363 causing them to release and extinguish the supervisory lamps 384 and 378.

If, instead of sending a disconnect signal, the operator at either customer's station wishes to recall the toll board operator, the recall key 120 (Fig. 2) at customer's station C may be opened for a period of time sufficient to allow slow operating relay 362 or 363 (Fig. 3) respectively to operate the corresponding supervisory lamp 384 or 378, the supervisory lamp, under these conditions, might be flashed by operating and releasing the recall key slowly several times in succession.

Telegraph toll line circuit

One terminal of a telegraph toll line circuit is shown at J of Figure 5 (see also J in Fig. 1). As shown on the drawings, two polar relays are used, so connected as to form a differential polar duplex terminal set. It should be understood that this portion of the drawings is intended only to indicate such a terminal set or repeater in schematic form. Any of the well-known forms of duplex sets can be used and, in fact, any type of line circuit capable of transmitting signals in both directions could be used. For example, a metallic two wire line equipped for duplex operation

might be used, or two wires, each arranged to send signals in one direction. A full duplex carrier telegraph channel might be used or even a two-way radio telegraph channel. It is thought that the method of arranging this circuit to operate over any of these types of line system will be obvious to those familiar with the art.

In the normal or idle condition of the line, the winding of the pole changer relay 385 is connected through jack contact 386 of jack 387. Pole changer 385 is also connected by a circuit traceable through contact 386, conductor 388, (which also extends through contacts similar to 386 of any intermediate jacks which may be placed in the circuit at point indicated by broken line 708—it should also be noted that additional lamps may also be inserted at this point) contact 389 of jack 390, conductor 391, resistance 392, winding of busy relay 393 to ground 394. Busy relay 393 is a sensitive relay that will operate on a small current. It, therefore, remains operated to keep the busy lamps 395 and 396 extinguished while the line is idle and at the same time places a ground on winding 398 of pole changer 385. Under these conditions, however, the current from the lower or biasing winding 397 of pole changer 385 is stronger than that in the upper or line winding 398 and therefore the pole changer armature 399 remains against its positive or spacing contact, 400. Current from the positive current source 401 passes through resistance 402 and contact 400 to noise-killer 403, and in parallel through windings 404 and 405 of line relay 406 to line 407 and artificial line 408 respectively. The line relay 406 is not affected by this current but as the pole changer at an identical station M (not shown), at the distant end of the line, is also against its spacing contact, the armature of the line relay at station M corresponding to relay 406 at station J, viz. 406M will also be against its open or spacing contact, and the "receiving leg", or in other words, the conductor 409M leading to the tip of jack 387M will be open.

If the cord plug 412 (Fig. 4) is inserted in toll line jack 387, a current from source 414 will be carried over conductor 410 to sleeve of cord plug 412, in other words, the "sending leg" of the duplex set will be connected through contact 411 to the sleeve of jack 387, and if the sleeve of plug 412 is connected through a suitable resistance to ground, this ground will be placed on winding 398 of pole changer 385 through contact 411 of jack 387 and conductor 410, and the circuit will be completed through resistance 413, current source 414 and ground 415. It is to be noted that resistance 698 connected between current source 414 and winding 397 of pole changer 385 is of much higher resistance than resistance 413, and it is to

be further noted that ground 478 replaces ground 394 which is associated with the busy relay 393 and that resistance 699, associated with ground 478, is a lower resistance than resistance 392 associated with ground 394. Consequently, with the placing of ground 478 on winding 398, more current flows through this winding than through winding 397, and armature 399 is therefore operated against its negative or marking contact 416. This will operate the line relay 406M at the distant end of the line to close the receiving leg 409M which will in turn energize call lamp relay 417M to light the call lamps 418M and 419M. The circuit for operating relay 417M may be traced as follows: ground 420M, source of potential 421M, resistance 422M, contact 423M, conductor 409M, contact 424M of jack 387M, conductor 425M, contact 426M of jack 390M, conductor 427M, winding of relay 417M through resistance 428M to ground 429M. It should be noted that the insertion of the cord plug 412M into jack 387M will release the busy relay 393M breaking jack contact 386M consequently lighting the busy lamps 395M and 396M, over a circuit traced from ground 430M through current source 431M, conductor 432M, resistances 433M and 434M, busy lamps 395M and 396M, conductor 435M, contact 436M to ground 394M. It will be noted that the insertion of plug 412M into jack 387M will also operate pole changer 385M at the distant end of the line to send a marking signal back over line 407 to relay 406 in circuit J. The further operation of the toll line circuit can best be explained in connection with the operation of the cord circuits.

Station to toll line cord

The cord circuit for establishing a connection between a customer's station and a toll line is shown as circuit I in Figures 3 and 4. If a customer's station C (Fig. 2) has initiated a toll call and the customer's station line 102 has been extended through concentration board D over a switching trunk circuit F to the toll board as previously described, this call may be answered by means of a "station to station" cord or by means of a "station to toll line" cord. If the former is used, it will be necessary for the operator to change plugs as soon as she finds out that the customer wishes a long distance connection. In either case, cord plug 231 (Fig. 3) of "station to toll line" cord I will ultimately be inserted into switching trunk jack 210 (Fig. 2). The insertion of plug 231 into jack 210 closes contact 236 and, as previously described, places a positive potential on the sleeve of plug 231 through current source 221 of switching trunk circuit F. This current is passed from the sleeve of cord plug 231 over conductor 233 (Fig. 3) through the

windings of relay 451, through conductor 452 and through the windings of marginal relay 234 to ground 235 operating relay 234. Relay 451 will also be operated to close contact 453 which operates a circuit from ground 454 through positive potential 455, resistance 456, contact 453, conductor 457, contact 458 and so through supervisory lamp 459 to ground 460. Thus the supervisory lamp 459 5 will be lighted immediately on connections being made between cord circuit I and switching trunk F. Relay 234, by closing contact 443 connects a positive current from current source 437 (Fig. 4) to the customer's station line 102 (Fig. 2) through a circuit traced as follows: ground 438, current source 437, resistance 439, conductor 440, contact 441, conductor 442, contact 443 (Fig. 3) conductor 444, contact 445 of monitoring 10 key 312, conductor 446, contact 447, conductor 448, winding of relay 449, conductor 450 to cord plug 231 and so through switching trunk circuit F (Fig. 2), concentration board D to customer's line 102. This circuit 15 also operates relay 449 (Fig. 3) which closes contact 461, which places ground 462 on relay 463, which in turn opens contact 458 to extinguish supervisory lamp 459. The operator at cord I may, however, communicate 20 with the calling customer's station by operating monitoring key 312 if necessary.

Cord plug 412 (Fig. 4) is now inserted into the jack 387 (Fig. 5) of an idle toll line to the desired distant city. Repeating relay 35 464 (Fig. 4) in cord circuit I operates like relays 257 and 258 of station to station cord circuit H, which was previously described and therefore its method of operation need not be described here in detail. Winding 465 40 of relay 464 corresponds to windings 263 and 265 of relays 257 and 258 respectively, winding 466 of relay 464 corresponds to windings 264 and 266 of relays 257 and 258 respectively, and winding 470 of relay 464 corresponds 45 to windings 305 and 295 of relays 257 and 258 respectively, and the corresponding windings have approximately the same resistances. It should be noted, however, that as line relay 406 of the toll line is released 50 when plug 412 is first inserted in jack 387, the "receiving leg" 409 (Fig. 5) of the duplex set is open and there will be no current through the two windings 465 and 466 of relay 464 (Fig. 4) but the relay will be held 55 operated by a current from source 437 passed over conductor 467, through resistance 468, conductor 469, through winding 470 of relay 464 to ground 471. The contact 472 of relay 464 being closed, a circuit may be traced 60 from ground 415 (Fig. 5) associated with pole changer 385 through current source 414, resistance 413, winding 398 of pole changer 385, conductor 410, contact 411, sleeve of cord plug 412 (Fig. 4), conductor 473, contact 472, conductor 474, contact 475, con-

ductor 476, through supervisory lamp 477, to ground 478, which will be lighted, indicating to the toll board operator of cord I that the distant toll operator at station M has not yet answered. Supervisory lamp 477 70 is shunted by resistance 699 so that pole changer 385 will receive its normal working current of about 60 milliamperes without passing excessive current through lamp 477. 75

Since ground is placed on the line winding 398 (Fig. 5) of pole changer 385 it will operate and send a marking impulse over line 407 to station M. The marking signal transmitted by pole changer 385 will cause line relay 406M to close contact 423M, thus operating relay 417M and lighting the call lamps 418M and 419M. The operator at station M will respond by plugging cord plug 412M into toll line jack 387M. In this case, as line relay 406M is operated closing contact 423M, and sleeve relay 234M (Fig. 3) of the station to toll line cord circuit I is not operated, the repeating relay 464M (Fig. 4) will be held operated through its righthand winding 465M and through the back contact 479M 80 of relay 234M to ground 480M. Relay 481M also operates over a circuit traced from junction point 482M through winding 466M of relay 464M, resistance 483M, inductance coil 484M, winding of relay 481M to ground 485M. The operation of relay 481M will close contact 486M to place ground on slow release relay 487M over a current operating from ground 485M to contact 486M, through conductor 488M, winding of relay 487M, conductor 489M, resistance 490M, conductor 491M and through source of potential 437M to ground 438M. Relay 487M will then operate to break contact 475M, removing supervisory lamp 477M from the sleeve circuit of jack 387M (Fig. 5) and replacing the ground 478M (Fig. 4) associated with the supervisory lamp 477M by ground 491M through resistance 492M at contact 493M. The supervisory lamp 477M is thereby extinguished, 90 and pole changer 385M operates. 95

The operation of pole changer 385M (Fig. 5) sends a marking signal back over line 407 to operate the line relay 406. This closes the "receiving leg" 409 connecting positive current from current source 421, through contact 423, over "receiving leg" 409, through jack 387, to tip of plug 412 (Fig. 4) and so to windings 465 and 466 of relay 464. The relays 481 and 487 will be operated as previously explained in connection with the operation of station M, the latter relay extinguishing supervisory lamp 477. Relay 487 will also extend the receiving leg circuit 409 from winding 465 of relay 464, over conductor 702 through junction point 730, conductor 731, contact point 496, conductor 442 and contact point 443 (Fig. 3) and so through monitoring key 312 to the line circuit extending to the calling customer's station C. 105 110 115 120 125 130

With the monitoring keys 312 operated, the toll operators at both stations make contact with each other by printer over the toll line 407 and their conversation will be recorded by the printer at the calling subscriber's station. If it is desired to avoid having this conversation reported at the calling subscriber's station, the outward operator may operate split key 315 (Fig. 4) in a direction to operate the right-hand springs, closing contacts 358, 359 and 360 and thus connecting a positive current through relay 342 (Fig. 5) to the calling customer's station line 102 and connecting station M through cord plug 412 and the operator's printer 307 to ground 346 (Fig. 5) as previously described.

After the outward operator has transmitted the number of the called station, the operator at station M will connect plug 231M (Fig. 3) to an idle switching jack 210M (Fig. 2) and establish a connection to the called subscriber's station C in the same manner as previously described for local calls. When the cord plug 231M is inserted into jack 210M, sleeve relay 234M does not operate until switching trunk F at the distant station is plugged up at the concentration board, at which time it does operate to extend the toll line circuit through to the called subscriber's station C starting the station motor in the usual manner, as previously described.

The customers' stations may now communicate with each other by printer. The outgoing printer signals through each station operating repeating relay 464 (Fig. 4) of the cord circuit I, which will in turn open and close the "sending leg" circuit at contact 472 to operate pole changer 385. Incoming signals from the toll line 407 (Fig. 5) will operate line relay 406 which will repeat these signals over the receiving leg circuit 409 directly through the windings 465 and 466 of relay 464 (Fig. 4) to the station line 102 (Fig. 2) without operating relay 464, as previously described in connection with repeating relays 257 and 258 (Fig. 3). It will be seen, therefore, that relay 464 is in effect a "half set repeater" and has the effect of converting the full duplex circuit into a half duplex circuit. The operators at the two customers' stations C may both transmit and receive but both cannot transmit at the same time. The toll board operators at the two central stations should cut out of the circuit by restoring their monitoring keys 312 as soon as communication is satisfactorily established.

The outgoing signals will operate marginal relay 449 (Fig. 3) as previously described, and the incoming signals from the distant station will operate relay 481 (Fig. 4) as well as relay 449. Relays 449 and 481 will send impulses through the windings of re-

lays 463 and 487 respectively. The latter relays are both of the slow release type, however, and will not release on printer signals. If the operator at either of the customer's stations should wish to recall his toll board operator, he may do so by slowly opening and closing the contacts of the recall key 120 (Fig. 2) at customer's station C. This will release marginal relay 449 (Fig. 3) for a sufficient interval to allow relay 463 to release and light the supervisory lamp 459, as previously described. It will also release relays 481M (Fig. 4) and 449M at the distant end of the line. This will permit relay 487M to release, closing contact 475M and thus lighting supervisory lamp 477M. Relay 487M also connects positive current from source 437M to relay 449M (Fig. 3) through resistance 439M (Fig. 4), conductor 440M, contact 441M, conductor 442M, contact 443M (Fig. 3) conductor 444M, contact 445M, conductor 446M, contact 447M, and conductor 448M, thus operating relay 449M. Relay 463M should preferably be adjusted to be slightly slower to release than relay 487M (Fig. 4) so that relay 449M may operate in time to prevent relay 463M from releasing. It is evident, therefore, that the operation of the recall key 120 at the customer's station C will flash supervisory lamp 459 (Fig. 3) at the near toll board and the supervisory lamp 477M (Fig. 4) at the distant toll board. Such a local signal may be answered by the operator by means of monitoring key 312 (Fig. 3) and if trouble is being experienced, split key 315 (Fig. 4) may be operated, if necessary, to determine whether the trouble is in the local station circuit or on the toll line circuit.

At the conclusion of the call both stations should clear the circuit by restoring their call keys 141 (Fig. 2) to normal and momentarily operating the release portions of keys 141, thus releasing contacts 142 and closing contacts 156. This will lock up relay 131 and release the control relay 128 at each customer's station to stop motors 140 and reduce the line current, as previously described, by inserting high resistance windings 104 of relays 101 into the circuits. The reduction in the line current will release marginal relay 449 (Fig. 3) of station to station toll line cord circuit I. The station which first disconnects will also release relay 464 (Fig. 4) which will in turn open contact 472 and thus open the sending leg circuit and cause pole changer 385 (Fig. 5) to release and armature 399 to close its circuit at contact 400, thus sending a spacing signal over toll line 407 to the other station. This will release relay 406 at the distant end of the line with the result that the receiving leg circuit will be opened at contact 423, and thus stopping the flow of current from source 421, through windings 465 (Fig. 4) and 466 of relay 464. quently relay 464 will be held operated by winding 470, as previously described. Relays 481 and 487 will release, however, to light supervisory lamp 477, as previously described. The supervisory lamp 459 (Fig. 3) at one station is now lighted as well as supervisory lamp 477 (Fig. 4) at the second station. When the second station disconnects, relay 449 (Fig. 3) at that point will release and, after an interval, relay 463 will release and light supervisory lamp 459, as previously described. This will have no effect on the toll line circuit, however, as relay 464 (Fig. 4) is held operated as previously described. When both subscribers have cleared out, both supervisory lamps will be lighted at one toll board and supervisory lamp 459 (Fig. 3) alone lighted at the other board. Both operators should then pull down their cords, restoring the circuits to normal.

Toll line to toll line cord

For establishing through connections between two central stations the toll line to toll line or "through" cord shown as circuit K (Fig. 4) should be used. The operator will normally answer such calls with the station to toll line cord I, previously described, and on finding that a through connection to a distant city is desired ascertains the station wanted and then substitutes a through cord K.

It will be understood that the two cord plugs 494 and 495 of this circuit are, when the cord is connected, plugged into jacks 387 (Fig. 5) of two separate toll line circuits J. In this cord circuit, the tip of cord plug 494 (Fig. 4) is connected to the sleeve of the cord plug 495 and vice versa so that when two toll line circuits are interconnected, the "sending" leg of each toll line is interconnected to the "receiving" leg of the other toll line, sufficient resistance being included in the cord circuit to lower the current in the pole changer 385 (Fig. 5) to the usual value of about 60 milliamperes. Under these conditions the two duplex sets are connected together so as to form a full duplex repeater and incoming signals from either toll line will be repeated through to the other line. It is to be noted that this circuit operates differently from station to toll line cord circuit J which as previously pointed out operates over the same toll line as a half duplex repeater by reason of relay 464 which will repeat signals only in one direction.

The relays in the cord circuit K are not used for repeating signals from one toll line to the other but serve to enable the local operator to connect her printer into the circuit for sending and receiving and to operate the supervisory lamps.

As the sleeves of both cord plugs 494 and 495 are used for repeating signals, a simple

sleeve relay such as relay 234 (Fig. 3) used in circuit I or relays 251 and 259 used in circuit H cannot be used. A relay is needed, however, to disconnect the local circuits to save current when the cord is not in use and to extinguish the supervisory lamps. Relays 496 and 497 serve this purpose. These relays each have two windings, one of low resistance 498 and 499 and one of high resistance 500 and 501, and are capable of operating on a low current. The same type of relay as relay 101 (Fig. 2) in the customer's stations circuit C may be preferably used for this purpose, but it is not necessary to use a polar relay if a sufficiently sensitive neutral relay is available.

Assuming that plug 494 has been plugged into a toll line jack 387 (Fig. 5) over which a call has been received from a distant central station, current from source 414 associated with ground 415, will be passed through resistance 413, winding 398 of relay 385, conductor 410, contact 411 of jack 387, to the sleeve of plug 494 (Fig. 4) and so over conductor 510 through winding 511 of relay 512 and through windings 498 and 500 of polar relay 496 in series aiding, and so through resistance 520 to ground 521. Relay 496 will be operated but since the high resistance winding 500 of this relay and resistance 520 in series with it, hold the current to about 3 milliamperes relays 385 (Fig. 5) and 512 (Fig. 4) will not operate. On the operation of relay 496 contact 538 is closed and ground 521 is resultingly placed on a circuit traced as follows: from contact 538 to junction 801, conductor 550, winding 549 of relay 522, conductor 548, winding 547 of relay 523, conductor 546, winding 545 of relay 508, conductor 544, winding 543 of relay 512, conductor 542, resistance 541 and through current source 540 to ground 806. This places a biasing current of about 30 milliamperes on the four relays just mentioned. The closing of contact 538 also closes a circuit traced from current source 525 associated with ground 524, through winding 527 of relay 522, conductor 528, winding 529 of relay 523, conductor 530, contact 531, resistance 533, junction 552, conductor 534, junction 536, contact 538 to ground 521. This circuit places a current of about 60 milliamperes on windings 527 and 529 of relays 522 and 523, respectively, operating them and closing the two cord circuits at contacts 503 and 517, respectively.

It may be assumed that plug 495 will be plugged into an idle jack 387 (Fig. 5) of an idle toll line connected to the distant called station before slow operating relays 559 (Fig. 4) and 560 (since the operator has ascertained the name or number of the called station before plugging up either plug or cord K) can operate, in which case the circuit from the tip of plug 494 to the sleeve of plug 495 will be closed and the circuit from

the incoming line plug 494 to current source 421 (Fig. 5) and ground 420 being closed at contact 423 a current of approximately 60 milliamperes is thus placed on relays 497 (Fig. 4), 508 and 385 (Fig. 5) of the outgoing toll line, operating them. The operation of relay 508 and the consequent opening of contact 585 will prevent relay 560 from operating, but since contact 423 (Fig. 5) of the outgoing line will not be closed until the called station answers, and until this circuit is completed by the closing of 423 sufficient current will not be placed on the line to operate relay 512 (Fig. 4) and so prevent relay 559 from operating. Relay 559 will therefore operate over a circuit traced from ground 806, current source 540, conductor 528, resistance 581, winding of relay 559, conductor 580, contact 579, conductor 577, contact 538, to ground 521, to close contact 594 and thus light lamp 561 associated with plug 495 over an obvious circuit the current for which is supplied by source 540, and by closing contact 584 will also place ground on conductor 575 over a circuit comprising ground 521, contact 538, conductor 577, conductor 583 and contact 584. Relay 559 will also lock itself through contact 802, conductor 555, contact 554, conductor 553, junction 552, conductor 534, junction 536, contact 538 and ground 521.

The operator should now throw the monitoring key 321 to open this locking circuit at contact 554 and connect receiving relay 318 into the circuit. When relay 385 (Fig. 5) of the outgoing line is operated, as above described, a negative potential from source 803 will be applied to toll line 407 and will light lamp 418 at the distant called station to advise the operator of an incoming call as previously explained. When the distant operator answers by plugging into toll line jack 387 at the distant end of the line, a negative current is sent over the line in the reverse direction operating relay 406 at the intermediate station which will in turn place current from source 421 on the tip of plug 495 (Fig. 4) by closing contact 423 (Fig. 5) thus carrying a current of about 60 milliamperes over conductor 409, contact 424, tip of cord plug 495, conductor 518, contact 517, resistance 515, junction 519, winding 498 of relay 496, conductor 513, winding 511 of relay 512, conductor 510, to sleeve of cord plug 494 and so through contact 411 of a toll line jack 387 (Fig. 5), conductor 410, winding 398 of relay 385, resistance 413, negative current source 414 to ground 415, the increased current over the circuit just traced operating relays 512 (Fig. 4) and 385 (Fig. 5) of the incoming toll line. The operation of relay 385 will send a negative impulse over a toll line 407 to the distant calling station where the calling lamp 418 will be operated to advise the operator that the distant called

station has answered. The relay 512 (Fig. 4) on being operated will release relay 559 (the locking circuit for relay 559 having already been broken at contact 554 of monitoring key 321) by breaking contact 579 and relay 559 will in turn remove ground from the circuit of lamp 561 by opening contact 594, thus indicating to the operator at the intermediate station that called station has answered. 75

When the monitoring key 321 is operated, contact 531 is opened but the circuit of windings 527 and 529 of relays 522 and 523 respectively is extended through contact 804 over conductor 324, key 325 through operator's transmitter contacts 307, conductor 326, contact 327, conductor 328, contact 329 (Fig. 3) conductor 330, contact 805, conductor 556, through resistance 557 to ground 558. Printer signals sent from the operator's transmitter contacts 307 will then operate sending relays 522 and 523, which will interrupt the two cord circuits at contacts 503 and 517, respectively, to operate the pole changers 385 (Fig. 5) in both toll line circuits thus enabling the operator at the intermediate station to transmit printer signals over both toll lines 407. It is to be noted that split key 315 should not be used in conjunction with cord circuit K. 85

Relays 512 and 508 are used for receiving signals to be recorded by the operator's receiving printer 578 and also for controlling relays 559 and 560 which operate supervisory lamps 561 and 562 respectively. The upper windings 511 and 507 of these relays are inserted in the cord circuits as previously described, so that the relay 512 responds to signals from the line relay 406 (Fig. 5) of the toll line associated with cord plug 495 (Fig. 4) and relay 508 responds to signals from the line relay associated with cord plug 494. Since the terminal toll stations which are connected through cord circuit K are each utilizing a station to toll line cord such as I, signals can be transmitted in only one direction, at a time, by reason of the use of "half-set" relay 464 and as a result only one of these relays will be operated at a time, the armatures of the other relay being held against its marking contacts 563 of relay 512 or 564 of relay 508. 115

When no signals are being transmitted, the armatures of relays 512 and 508 will be held against their marking contacts just mentioned. Under these conditions, if monitoring key 321 is operated, current from source 565 (Fig. 3) associated with ground 566 will flow through resistance 567, conductor 568, contact 569, conductor 310, contact 311, conductor 313, contact 314 of split key 315, conductor 316, winding 317 of relay 318, conductor 319, contact 570, conductor 571, resistance 572, back contact 573 of relay 560, front contact 564 of relay 508 to junction point 574, 135

conductor 575 to back contact 576 of relay 559 to front contact 563 of relay 512, conductor 577 to contact 538 of relay 496 and so to ground 521. This will hold line relay 318 and line magnet 578 of the operator's printer energized. If signals are now received over the toll line associated with cord plug 495, relay 512 will respond to these signals opening and closing contact 563 in the circuit just traced, thus causing the signals to be recorded on the toll board operator's printer. Similarly if signals are received over the toll line associated with cord plug 494, relay 508 will respond to these signals and repeat them in like manner into the operator's printer. When communication is satisfactorily established between the two distant stations the operator's printer at the intermediate station can be cut out of the circuit.

As previously pointed out relays 512 and 508 in responding to printer signals will also send impulses through the windings of relays 559 and 560 respectively. It is to be noted that relays 559 and 560 are of the slow to operate type and are so designed that they will not operate on printer signals. If, however, the customer's station C connected to the toll line associated with cord plug 494 should clear out this will send a continuous spacing signal over the toll line which will release relay 508 and after an interval will operate relay 560 over a circuit similar to the operating circuit of relay 559, previously traced, and by closing contact 591 will place ground 592 in the circuit thus lighting supervisory lamp 562 associated with cord plug 494. Relay 560 locks itself through contact 593 and ground 539 which is connected over a circuit including contact 537, conductor 534, conductor 533, contact 554 of key 321, and conductor 555. The toll board operator can thus receive signals on her printer set from relay 512, even though relay 508 is released. Similarly, if the customer's station C connected to the toll line associated with cord plug 495 should clear out or the distant operator should pull down the cord associated with the toll line, relay 512 will release and after an interval, relay 559 will close contact 594, placing ground 595 in the circuit and lighting supervisory lamp 561. Relay 559 will also close contact 584 thus connecting the armature of relay 512 through conductor 583, contact 584 and conductor 575 directly to the armature of relay 508 as previously described so that the armature of relay 508 now is connected to ground regardless of whether relay 512 is operated or not. This permits relay 508 to repeat signals into the operator's printer or to operate its slow acting relay 560 regardless of whether relay 512 releases first or not.

The supervisory lamps 561 and 562 may, therefore, light either due to a clear out or recall signal. As relays 559 and 560 are

self-locking, the lamps will remain lighted. In either case, however, the operator can distinguish between these two conditions by operating the monitoring key 321 which removes the locking circuits from relays 559 and 560 by opening contact 554. This will extinguish the lamps if the line circuits are now closed as in the case of a recall signal, but the lamps will remain lighted in the case of a disconnect signal. In the latter case, the operator should pull down both cords which will release relays 496 and 497 which in turn will cause the other relays to release and extinguish lamps 561 and 562.

Station line with selective calling

With the arrangements previously described, all messages to or from a customer's station C are handled through the same concentration board by the same group of central station printers. If these concentration boards and these printers are located in the office of the telegraph company, there may be some delay in handling those messages that must be forwarded to a cable company for transmission. It may be preferable, therefore, in some cases to provide concentration boards and printers for each telegraph company or cable company and to provide means so that each customer can directly select the board at which his call will be answered. Each customer's line might then be arranged so that the customer can choose whether each of his calls will be answered at any of these boards or directly at the toll board. If desired the system could be arranged so that the customer can also call directly certain other departments of company, as for example, the repair department in case of trouble with equipment, etc.

A circuit for selective calling is shown in Fig. 6. Customer's station circuit O is similar to that shown as circuit C in Fig. 2 except that a telephone dial 660 has been added. The station line circuit extends over customer's station line 602 through the jacks 661 and 662 of toll board 663, jacks 664 of cablegram concentration board 665, jacks 666 of telegram concentration board 667 and finally through the winding of marginal relay 668, resistance 669, conductor 670 to negative current source 671. It is obvious that in case of an outgoing call from the toll board 663 or the concentration boards 665 and 667 to customer's station circuit O, the equipment would operate exactly as in the arrangements shown in Fig. 2 as previously described.

In the case of a call from customer's station O, however, dial 660 is used to select the board at which the call will be answered. In making such a call, the calling key 641 is operated in a direction to close contact 642 and this shunts out high resistance winding 125

110

115

120

125

130

604 of relay 601 and removes a short-circuit from the dial contacts by opening contact 672. This increases the line current which operates relay 668 at the central office, which 5 in turn operates slow release relay 673. The operator at customer's station O now operates a dial 660 to send one to ten pulses. The dial contact 674 opens and closes the line circuit to operate relay 668. Relay 601 at 10 the customer's station O will also operate in response to these pulses but this will have no effect as the circuit of control relay 628 is held open by the "off normal" contacts 675 of the dial 660 while the pulses are being 15 transmitted.

Relay 668 operates in response to the dial pulses and sends pulses through its back contact 676 and through the front contact 20 677 of relay 673 to operate the rotary magnet 678 of the selector 679. The selector has a wiper which can rotate over a bank of ten contacts 681. The wiper 680 rotates one step 25 for each operation of the rotary magnet 678 and is held by a pawl which can be released by operating release magnet 682 allowing the wipers 680 to return to normal. The "off normal" contacts 683 of selector 679 close on 30 the first rotary step of the selector and remain closed until the selector returns to normal.

With the selector bank contacts 681 as shown, it is obvious that if two impulses are sent from the customer's dial 660, the selector wiper 680 will rotate two steps and close a circuit for lighting call lamp 684 at cable-gram concentration board 665, while if ten 35 impulses are sent, the call lamps 685 and 686 at toll board 663 will be lighted. It is also clear that additional call lamps up to a maximum of ten may be selectively operated to 40 direct the call to a corresponding number of switchboards by using the remaining bank terminals of the selector.

After a call lamp has been operated as described, the call can be answered by inserting a plug into the jack at the selected board using a cord circuit similar to that of central station printer circuit G shown in Fig. 2, at the concentration boards or any of the station cords, shown in Figs. 3 and 4 at the 45 toll boards. This will reverse the current on the station line, releasing relay 601 at customer's station O and operating control relay 628 to start printer motor 640 at the station. It will also release relay 668 which 50 after an interval, releases relay 673 and closes a circuit for operating release magnet 682 of selector. This permits the wiper 680 to restore to normal and extinguishes the call lamp. The "off-normal" contacts 683 of the 55 selector open the circuit and release magnet 682 when the selector has been restored to normal. Busy relay 687 also operates in series with the sleeve circuits 688 of the jacks 661, 662, 664 and 666 and lights busy lamps 689, 690, 691 and 692 associated with this line 60

at all switchboards, by closing contact 693 which passes current from source 694 through the various busy lamps to their respective grounds.

At the conclusion of the call the calling key 641 should be restored to its normal position at customer's station O and in the case of a toll call, the key should be operated to its "clear-out" position momentarily closing contact 656 to operate relay 631 which locks itself through contact 659 and releases the control relay 628 causing supervisory lamps 459 (Fig. 3) 378 or 384 at the toll board to light as previously described. In the case of a call through concentration board 665 and 667 (Fig. 6), however, it will not be necessary for the customer's station O to send the "clear-out" signal as the main station operator will operate her key to light the disconnect lamp 197 (Fig. 2) associated with the cord at the concentration board. This will also operate relay 601 (Fig. 6) at customer's station O and stop station motor 640 as previously described. When the cord plug, inserted in concentration board jacks 664 or 666, is pulled down, relay 668 is connected back into the circuit but the control relay 628 at customer's station O having released relay 668 will not operate. 95

What is claimed is:

1. In a telegraph system, the combination of the first central station, a second central station, a two-way telegraph line connecting said central stations, transmitting and receiving printers at each of said stations, supervisory signal means at each of said stations, means for operating the line circuit between said stations full duplex for the purpose of controlling the supervisory signal means, and means for automatically converting the said line circuit for half duplex operation. 100

2. In telegraph system, the combination of a first central station, a second central station, a plurality of local stations associated with each of said central stations, a telegraph line connecting each of said local stations with its associated central station, a telegraph line circuit connecting said central stations, transmitting and receiving printers at each of said stations, supervisory signal means at each of said central stations, means for operating the line circuit between said central stations full duplex for the purpose of controlling said supervisory signal means, means for automatically converting the said line circuit for half duplex operation, and means for interconnecting two local stations respectively associated with said first and said second central stations over said converted line circuit. 115

3. In a telegraph system, the combination of a first central station, a second central station, a third central station, a telegraph line connecting the first and second station, a telegraph line connecting the second and 120 125 130

third station, telegraph transmitting and receiving apparatus at said second station, supervisory signal means at each of said stations, a link circuit and a pair of terminal

5 duplex sets at the second station, means for connecting said link circuit with said terminal duplex sets whereby said link circuit forms with said sets a full duplex repeater adapted to relay messages between the first

10 and third stations, means for connecting said transmitting and receiving apparatus into the said link circuit whereby the second station may transmit simultaneously in both directions, and may receive from either terminal

15 station, and means for independently operating from the first or third station the supervisory signal means at the second station to indicate the signalling station.

4. In a telegraph system, the combination 20 of a first central station, a second central station, a third central station, a telegraph line connecting the first and second station, a telegraph line connecting the second and third station, transmitting and receiving 25 printers at each of said stations, a pair of terminal duplex sets and a link circuit at the second of said stations for establishing a through connection between the first and third stations, supervisory signal means associated with said link circuit, means for connecting said link circuit and said terminal duplex sets whereby said link circuit and said sets form a full duplex repeater in relaying messages between the first and third stations,

30 35 means for connecting a printer into said link circuit whereby the second station operator may transmit simultaneously in both directions or receive from either terminal station, and means for independently operating from the first or third station the supervisory signal means to indicate the signalling station.

5. In a telegraph system, the combination of 40 a central station, a plurality of local stations, a telegraph line connecting each local station with the central station, a relay at each of said local stations, a high resistance, and means at each local station and at the central station for short-circuiting the high resistance at the local station.

6. In a telegraph system, the combination 45 of a central station, a plurality of local stations, a line current supply for each of said local stations, and means whereby under the idle condition of the circuit the line current can be reduced either at the identical local station or from the central station.

7. In a telegraph system, the combination 50 of a central station, a plurality of local stations, a telegraph line connecting each local station with the central station, a line current supply for each local station furnished from the central station, supervisory signal means 55 at the central station, and means whereby the

strength of said current can be altered from each local station to operate the supervisory signal means at the central station.

8. In a telegraph system, the combination 70 of a central station, a plurality of local stations, a telegraph line connecting each local station with the central station, a plurality of switch boards and a directly controlled switch associated with each of said lines at the central station, calling signal apparatus 75 associated with each of said boards, and means at each local station for operating the associated switch to operate the calling signal apparatus associated with a predetermined board.

9. In a telegraph system the combination 80 of a central station, a plurality of local stations, telegraph lines joining the local stations with the central station, impulse transmitting means at each local station, selecting 85 means at the central station, a plurality of concentration boards at the central station, a plurality of toll boards at the central station, calling signal means at each board, and means whereby the operation of the impulse transmitting means at any local station will operate the selecting means at the central station to operate a predetermined group of calling signal means at the central station.

10. In a telegraph system, the combination 90 of a central station, a plurality of local stations, a telegraph line connecting each local station with the central station, a concentration board at the central station, a plurality of calling signal lamps located at said concentration board and operable from each local station, and means for independently operating from each local station any of the lamps associated with said station.

11. In a telegraph system, the combination 100 of a central station, a plurality of local stations, a plurality of printers and a concentration board at said central station, calling signal means at said concentration board associated with each of said printers, and means for operating said calling signal means only when the apparatus with which it is associated requires attention.

12. In a telegraph system, the combination 110 of a central station, a switchboard, a plurality of switchboard link circuits, a central station switchboard operator's printer set, a monitoring key associated with each link circuit, means common to said link circuits whereby connection can be made, through the various monitoring keys, between said printer set and either end of any one of said link circuits, and the other end of said link circuit disconnected.

13. In a telegraph system, the combination 120 of a central station, a toll board, a plurality of toll board link circuits, a toll board operator's printer set, means whereby said printer set can be connected into any one of said link circuits at will and whereby if an 130

attempt is made to connect the printer into two or more link circuits simultaneously, the printer will be connected with only one of said link circuits and means whereby the remaining circuits will be or remain closed.

14. In a telegraph exchange system, the combination of a plurality of central stations, a plurality of local stations each of which is respectively connected to a central station over a two-way telegraph wire, a concentration board, an operator's printer associated with the concentration board and a toll board at each central station.

15. In a telegraph exchange system, the combination of a plurality of central stations, each having associated therewith a plurality of local stations, a two-way telegraph line connecting each local station with its associated central station, a telegraph transmitting and receiving apparatus, and a printer motor for operating said apparatus at each local station, a polar relay with a high and low resistance winding in series with said telegraph line, means under control of a local station for short-circuiting the high resistance winding of said relay at said station, means under control of each central station for short-circuiting the high resistance winding of the relay at each of its associated local stations, means under control of each local station for reinstating said winding into the line circuit once it has been short-circuited, means under control of each of said central stations for reinstating said winding into the line circuit of its associated local stations once it has been short-circuited, means under control of each of said central stations for actuating said polar relays located at each of the local stations associated with said central station, and means for thereby starting the printer motor at each local station.

16. In a telegraph system, the combination of a central station, a toll board link circuit divided into a plurality of sections, each section having a differential polar relay to repeat signals from one section of the link circuit to the other, supervisory signal means associated with each of said polar relays, and means associated with each pair of differential polar relays, whereby said supervisory signal means may be operated independently of each other.

17. In a telegraph system the method whereby telegraph messages may be transmitted half duplex and supervisory signals transmitted full duplex over the same telegraph line, comprising the relaying of the telegraph signals through a half set repeater to an ordinary duplex circuit and the transmission of the supervisory signals directly to the duplex circuit.

18. In a telegraph system the method of long distance telegraph transmission comprising a circuit arranged for full duplex op-

eration, a change being made in the condition of the circuit for the purpose of calling the operator at the distant station, and the circuit being automatically converted to half duplex operation, when the connection is obtained, by the insertion of the half set repeater in the link circuit.

19. In a telegraph system the method of establishing through connections between two central stations at an intermediate central station, which comprises passing the telegraph signals at the intermediate station through a duplex repeater comprising two terminal duplex sets connected by a link circuit providing calling means associated with said terminal duplex sets for indicating the signalling station, and providing means for connecting a transmitter and printer into said link circuit to enable an operator at the intermediate station to send in both directions simultaneously and to receive from either direction.

20. In a telegraph system the method of controlling calling signal means located at a central station comprising the passing of a current through said means and over a single telegraph line to a local station and there through the high and low resistance windings of a polar relay, the high resistance winding of which can be short-circuited either from the local station or from the central station thereby applying sufficient current to operate the supervisory signal means.

21. In a telegraph system the method of predetermining where at the central station a local call is to be received, comprising transmitting a selected group of current impulses from the local to the central station, and causing said impulses to operate a calling signal at the preselected toll board or concentration board at the central station.

22. In a telegraph system, the method of supervisory signal control, comprising the use of a signalling current the strength of which may be altered from the local station, whereby different signal relays may be operated at the central station concentration board, thereby operating distinctive supervisory signals.

23. In a telegraph system, the method of connecting the central station toll board operator's printer set with the toll board link circuits, comprising inserting a monitoring key into each toll board link circuit and so connecting said operator's printer set circuit with said monitoring keys that on the operation of a particular key said printer set will be connected into the link circuit associated with said key and with only one of said link circuits if more than one key be operated, the remaining unconnected link circuits, in such case, being closed.

24. In a telegraph system, the method of recalling the central station printer set operator after motors at both the central and

local stations have been stopped, comprising increasing the line current at the local station to operate a marginal relay in the central station printer set circuit which causes 5 the line to be restored to its normal working condition and both said motors to be restarted.

25. In a telegraph system, the method of transmitting telegraph messages between two 10 local stations which comprises connecting the local station with a central station and the transmission of the telegraph signal current through a concentration board, switching trunk and toll board link circuit at the 15 central station and so over a toll line to a second central station where the telegraph signal current is passed through the same apparatus in reverse order and so to a local station associated with the second central 20 station.

26. In a telegraph system, the method of controlling central station toll board supervisory signal means, comprising the removal of a high resistance from the line connecting 25 the calling local station and the central station, and the connection of the switching trunk with said line through the concentration board whereby said signal means is operated to give a distinctive signal.

30. 27. In a printing telegraph exchange system, the combination of a first, second and third central station, a telegraph line connecting said first and second, and another connecting said second and third stations, 35 each of said lines terminating at one end in a terminal duplex set at said second station, a link circuit at said second station, having a calling and an answering cord, each with a normally open tip and sleeve circuit, means for 40 connecting said link circuit with said terminal sets, and means responsive to said connection for closing said tip and sleeve circuits and for causing said terminal sets to form a full duplex repeater for relaying signal impulses 45 over said lines.

28. In a printing telegraph exchange system, the combination of a first, second and third central station, a telegraph line connecting said first and second stations and another connecting said second and third stations, each of said lines terminating at one end in a terminal duplex set at said second station, a link circuit and toll board jacks 50 for interconnecting said terminal sets to form a duplex repeater for relaying signals over said lines, means for connecting a printer in said link circuit, and means in said link circuit for repeating signal impulses from either terminal set to said printer and from said printer to either or both of said terminal sets.

55. 29. In a telegraph system, a central station having a switching board and a plurality of link circuits each provided with a pair of terminals, a first and second station adapted

to be interconnected through said switching board and the terminals of any one of said link circuits, an operator's printer set common to said link circuits, a monitor key associated with each link circuit for connecting the operator's printer set to both the first and second stations through the terminals of the associated link circuit, and switching means in the printer set circuit for connecting said printer set to either said first or said second station and disconnecting it from the other station without removing the terminals of said link circuit from said switching board by connecting said printer set to either terminal and disconnecting it from the remaining terminal of the link circuit associated with the previously operated monitor key. 70

75. 30. In a telegraph system, a central station, a local station, a telegraph line connecting the local station with the central station, a polar relay connected in the line and a printer motor at the local station, means under control of said central station for operating said relay, means responsive to the operation of said relay for starting and stopping said printer motor, means under control of the local station for stopping the printer motor without operating said relay, and means under control of the central station 80 for thereafter operating said relay to restart the printer motor. 90

95. 31. In a printing telegraph exchange system, the combination of a central station, a local station connected therewith by a two-way telegraph line, a printer, a printer motor, and a polar relay having a high and a low resistance winding in series with said line at said local station, means under control of said central station for operating said 100 polar relay in either direction, means responsive to the operation of said relay in one direction for removing said high resistance winding from said line and for starting said printer motor, means responsive to the operation of said relay in the other direction for reinstating said high resistance winding in said line and for stopping said motor, and means operable from said local station for performing said last mentioned function 105 without operating said polar relay. 110

115. 32. In a telegraph system, a central station, a local station connected therewith by a telegraph line, a printer motor at said local station, means under control of said central station for starting and stopping said printer motor, and means under control of said local station for stopping said printer motor but conditioning said local station circuit for the restarting of said printer motor from 120 the central station. 125

130. 33. In a telegraph system, the combination of a central station, a local station, a normally energized telegraph line connecting said stations, means under control of said

- local station for increasing the current flowing in said line to the value used in signalling for supervisory and signalling purposes, and means under control of the central station 5 for similarly increasing said current for the purpose of preparing said local station for the reception of signal impulses. 70
34. In a telegraph system, the combination of a central station, a local station connected thereto by a normally closed line circuit, means at the local station for variably altering the strength of the line current and a plurality of calling lamps associated with the line at the central station and selectively operable in accordance with the current variations. 75
35. In a telegraph system, a central station for furnishing a plurality of classes of telegraphic service, a local station, a line connecting said station in which current having a smaller value than the signalling current is flowing, and means under control of said local station for variably altering the value of said current to determine which class of 20 service is to be supplied by said central station. 80
36. In a telegraph system, the combination of a central station, a local station, a telegraph line including a resistance connecting said 30 stations, supervisory means at said central station, means under control of said central station and other means under control of said local station for removing said resistance from said line, means responsive to the removal of said resistance by said local station for selectively operating said supervisory signal means, and means responsive to the removal of said resistance by said central station for preparing said local station for 35 the reception of signal impulses. 95
37. In a telegraph system, the combination of a central station, a local station connected thereto by a line normally including a resistance, a plurality of calling lamps permanently 40 associated with the line at the control station, means at the local station for removing the resistance from and then reinserting it in the line, and means at the central station responsive thereto for operating a predetermined one of the calling lamps. 100
38. In a telegraph exchange system, the combination of a plurality of central stations, each having associated therewith a plurality of local stations, a concentration board and 45 a toll board at each of said central stations, a two-way telegraph line connecting said local station with its associated central station and terminating in the concentration board at that station, a toll line circuit terminating 50 at each end in a toll board at one of said central stations for interconnecting each pair of central stations, each of said central stations having in addition a switching trunk for interconnecting the concentration board 55 and the toll board at said station, a station- 105
- to-toll-line link circuit for interconnecting said switching trunk and the toll line circuit at the said station, a toll-line-to-toll-line link circuit for interconnecting two toll line circuits, and a station-to-station link circuit for 60 interconnecting two local stations associated with the said station. 110
39. In a telegraph system, a calling and a called station, an intermediate station having a repeater through which the calling and called stations can be interconnected, a supervisory lamp at the calling station, means for lighting the supervisory lamp when the calling station calls the intermediate station, means at the called station effective when said 65 station answers a call from the intermediate station for sending a signal back to the intermediate station from which it is retransmitted by the repeater to the calling station, and means at the calling station responsive to the reception of the signal for extinguishing the supervisory lamp. 120
40. In a telegraph system, a calling and a called station, an intermediate station through which the calling and called stations can be interconnected, a supervisory lamp at the intermediate station, means for lighting the supervisory lamp when the intermediate station answers a call from the calling station, means at the called station effective when said station answers a call from the intermediate station for sending a signal back to the latter station, and means at the intermediate station responsive to said signal for extinguishing said supervisory lamp. 125
41. In a telegraph system, a first station, a second station and a third station, switching means for establishing a connection from said first to said third station through said second station, and means at said second station operative upon the response of said third station for causing an indication that said third station has answered, and means at said first station operative in response to said last mentioned means for causing an indication that said third station has answered. 130
42. In a printing telegraph exchange system, a first and a second central station, a duplex line circuit connecting said stations, said circuit terminating in a toll board at each of said stations, each station being provided with supervisory means and also a link circuit for establishing a connection with the toll board at said station, means responsive to the interconnection of said link circuit and said toll board at said first station for operating the supervisory means at said first station and at said second station, and means responsive to the connection of the link circuit to the toll board at said second station for sending a retractive signal to release the previously operated supervisory means at said first station. 135
43. In a printing telegraph exchange system, a calling and a called station, means for 140

establishing a connection from said calling to said called station, means at the called station responsive to the establishment of said connection for starting the printer motor 5 thereat, and means at the calling station responsive to the operation of said motor starting means for indicating at the calling station that said motor starting means have operated.

10 44. In a telegraph exchange system, a central station having a concentration board, a customer's station connected to the central station by a line terminating in a jack on the concentration board, a switching trunk co- 15 operating with the jack for extending either an inward or an outward connection over the line to the customer's station, a supervisory lamp associated with the trunk, and means for lighting the lamp only when the trunk is 20 to be connected to or disconnected from the jack.

45. In a telegraph system, a switching trunk for aiding in the extension of a connection in either direction between a first and a 25 second telegraph station, a plurality of links between said switching circuit and said second station for extending a connection in either direction between said second station and said switching trunk, a supervisory 30 lamp associated with said switching trunk, means under control of said first station for lighting said lamp when a connection has been extended from said first station to said switching trunk but before said connection 35 has been extended beyond said trunk, means for automatically lighting said lamp when a connection is extended from said second station to said switching trunk, and means for automatically lighting said lamp when 40 the adjacent one of said links is disconnected from said switching trunk.

46. In a telegraph system, the method of transmitting signal impulses between and operating supervisory signal means at two 45 stations connected by a duplexed telegraph line, which comprises impressing a potential on said line to control the signal supervisory means at both stations, and then impressing signal impulses on the identical line.

50 47. In a telegraph system, the combination of a central station provided with a toll board, a station to station link circuit and a station to toll line link circuit co-operating 55 with said toll board, a first and a second station adapted to be interconnected through said toll board and either of said link circuits, a toll board operator's printer set, a monitoring key associated with each link circuit, and 60 a single means for connecting either said first or second station to said printer set through either terminal of any one of said link circuits and for disconnecting the remaining station from said printer set by disconnecting the remaining terminal from said 65

set without disconnecting either terminal from said toll board.

In witness whereof, I hereunto subscribe my name this 10th day of May, 1930.

GILBERT S. VERNAM.
